(57) CLAIM

I claim the ornamental design for a pellet grill, as shown and described.

DESCRIPTION

FIG. 1 is a front perspective view of a pellet grill.

FIG. 2 is a front elevational view of the pellet grill depicted in FIG. 1.

FIG. 3 is a rear elevational view of the pellet grill depicted in FIG. 1.

FIG. 4 is a top plan view of the pellet grill depicted in FIG. 1.

FIG. 5 is a bottom plan view of the pellet grill depicted in FIG. 1.

FIG. 6 is a left side elevational view of the pellet grill depicted in FIG. 1; and,

FIG. 7 is a right side elevational view of the pellet grill depicted in FIG. 1.

The broken lines in the drawings illustrate portions of the pellet grill that form no part of the claimed design. The patterned grip portion of the central handle is shown in broken lines and forms no part of the claimed design.

1 Claim, 7 Drawing Sheets
